UNITED STATES PATENT OFFICE.

CARL POSTEL, OF NEW YORK, N. Y., ASSIGNOR TO AMERICAN SHALE REDUCTION COMPANY, OF NEW YORK, N. Y., A CORPORATION OF DELAWARE.

APPARATUS FOR EXTRACTING VOLATILE MATTER.

Application filed January 12, 1922. Serial No. 528,870.

To all whom it may concern:

Be it known that I, CARL POSTEL, a citizen of Germany, residing in the city of New York, county of New York, and State 5 of New York, have invented certain new and useful Improvements in Apparatus for Extracting Volatile Matter, of which the following is a specification, reference being had to the accompanying drawings, forming a 10 part thereof.

My invention relates to apparatus for extracting volatile matter from oil bearing shale and like material carrying volatile matter and has for its object to provide an 15 apparatus for this purpose which will be relatively inexpensive to construct and operate and will be effective to maintain an even, uniform and relatively low temperature throughout the treatment necessary to 20 extract the volatile.

With the above described objects and other objects hereinafter described in view, my invention consists in the construction and combination of elements hereinafter 25 described and claimed.

Referring to the drawings—

Figure 1 is a central vertical longitudinal sectional view of an apparatus embodying my invention and 30 Figure 2 is a cross sectional view near the forward end of the rotary retort.

In the drawings, 1 is a cylinder of metal preferably iron or steel open at both ends and having its ends adapted to rotate in 35 bearings 2 and 3 suitably supported by any convenient means (not shown) and inclined at a slight angle to the horizontal. Carried on the exterior of this cylinder and extending nearly to its ends is an outer cylinder 4 spaced a substantial distance from the exterior of cylinder 1 except at its ends, which are inwardly flanged and secured to the inner cylinder. Near its end nearest the upper end of cylinder 1 the outer cylinder 40 4 is provided with a filling opening closed by a screw plug 5. The space between the inner cylinder 1 and the outer cylinder 4 is filled with molten metal such as lead or other metal fusible at a relatively 45 low temperature.

Surmounting the inner cylinder 1 and outer cylinder 4, which together constitute a rotary retort, is an enclosing stationary plate 6 here shown a cylindrical for the 55 purpose of confining the heat supplied by

any convenient means such as burner 7 for gas or liquid fuel.

On the interior of the cylinder 1 is arranged an angle iron 8 extending longitudinally. More than one of these angle 60 irons may be used if desired.

Secured to the bearing 2 at the upper end of the retort is a hopper 9 adapted to contain a considerable quantity of the material to be treated. A sliding gate 10 carried by 65 a wall of the hopper extends in front of the open upper end of the retort nearly to its lower edge leaving an opening 11 for admission of the material to be treated, the size of this opening being regulated by adjusting the gate up or down.

Secured to the bearing 3 at the lower end of the retort is a discharge chute 12 into which spent material is discharged from the lower open end of the cylinder 1, the lower 70 end of this discharge chute leading to any convenient receptacle (not shown). From the upper closed end of the discharge chute a pipe 13 leads to a suction device here shown as a rotary pump 14 from which a 75 pipe 15 leads to a condenser 16.

The cylinder 1 is provided near its lower end with a sprocket wheel 17 which is connected by sprocket chain 18 with a sprocket wheel 19 which, through suitable gearing, is 80 driven by any convenient motive power such as the electric motor 20, shown.

In operation the space between the inner and outer cylinder 1 and 4 is filled with 85 molten lead, or other metal, which is kept in molten condition by the heat from burner 7 or the other heating means used. The hopper 8 being filled with finely divided shale or other material to be treated, feeds by gravity through the opening 11 into the interior of the cylinder 1, the mass of material in the hopper sealing this opening against entrance of air or escape of the gases or vapors generated in the retort. As the shale, or other material passes by gravity down the cylinder it is subjected to an even temperature which is kept uniform throughout the length of the retort by the molten lead, which, being liquid distributes the heat evenly thus avoiding any tendency 95 to overheating at any point or any drop of temperature below that desired, at any point. The angle iron 8 serves to agitate the shale as it passes down the interior of the cylinder and prevent it from accumulat-

105

110

ing at any point and by lifting the shale as the cylinder rotates and allowing it to fall through the heated gases within the cylinder aids in insuring that each particle of 5 the shale will be separately subjected to the heat.

The gases and vapors generated by the heat are drawn off by the exhaust pump 14 and are condensed in the condenser 16. The 10 spent shale falls from the lower end of the retort into the discharge chute, the lower end of which is suitably guarded against the entrance of air.

The molten lead being enclosed is not oxidized and there is consequently no appreciable loss from continuous use. The rotation of the retort probably causes more or less movement of the molten lead and aids in the action of the convection currents by 15 20 which heat distributes through the liquid lead as in other liquids.

The inclination at which the retort is arranged depends somewhat on the length of the retort, the inclination of a relatively long 25 retort being preferably greater than that of a relatively short retort.

The shale being subjected to an even, uniform temperature only slightly above that necessary to keep the lead in molten 30 condition, the volatile matter carried by it is completely extracted at a relatively low

temperature below that at which the volatiles tend to combine to form fixed gas, with the result that practically all of the volatiles combine to form condensable vapors. 35

While the apparatus is particularly adapted and intended for the treatment of the oil-bearing shale, it may, of course be used for treatment of other carbonaceous or earthy material carrying volatiles. 40

Having thus described my invention what I claim is:

In an apparatus for extracting volatiles from oil bearing shale and like material the combination with a retort arranged to rotate on an inclined longitudinal axis and having openings at its ends for admission and discharge of material to be treated, of a closed jacket enclosing the main portion of the retort and carried thereby containing molten metal, means for applying heat to the exterior of the jacket to maintain the metal in molten condition, means for rotating the retort and jacket to cause the heat applied to the jacket to be distributed evenly to all parts of the retort within the jacket, and means for drawing off from the retort the vapors produced therein. 45 50 55

In testimony whereof I hereunto affix my signature.

CARL POSTEL.
